BENJAMIN A. MOELLER, OF LOS ANGELES, CALIFORNIA

FOAM CONDUCTOR FOR OIL TANKS

Application filed November 7, 1927. Serial No. 231,697.

In the extinguishing of fires occurring in tanks containing oil, it is customary to produce a fire foam and to project it through the roof of the tank, usually at a point close to its side, in order to produce a layer of the foam over the surface of the burning oil.

It is well known that foam falling for a considerable distance, as for instance where the tank is only partly filled, is materially depreciated in value by breaking down as it forcibly strikes the surface of the oil, while if it is carried below surface it is likely to produce a serious and highly detrimental frothing.

To overcome this difficulty several devices have been proposed by means of which the foam may be lowered gently to a point just above the burning surface. The object of my invention is to provide a cheap and simple means for accomplishing this object, and the advantages of my invention will be apparent on inspection of the drawing appended hereto and the following description thereof. This drawing represents partly in elevation and partly in cross section a portion of a tank containing oil and my improved means for introducing foam onto the surface of said oil.

Referring to the drawing, 1 is the bottom of a tank, 2 is a section of its side wall, 3 is a section of a portion of its roof and 4 indicates the rim of the tank proper. The pipes 5 and 6 discharge two dissimilar foam producing solutions into a mixing head of usual or preferred design by which the solutions are thoroughly comingled and converted into foam. I would have it understood that this mixing head is no part of my invention and that the foam with which the fire is to be extinguished may be generated in any manner, in any kind of apparatus, and may be conducted over the rim of the tank by any convenient means.

8 is a pipe of a size proportionate to the size of the tank. For a tank of standard construction having a capacity of 55,000 barrels I prefer to use standard pipe of 15 inches diameter, but I do not restrict myself to any particular diameter of pipe nor to any particular material.

The lower end of this pipe should termi-

nate on or closely above the bottom 1 of the tank as indicated at 9. Through this pipe, and substantially throughout its length, perforations as indicated at 10 should be formed at substantially regular intervals, the spacing and diameter of these perforations being such that the area of the perforations in three lineal feet of the perforated pipe will equal the area of the foam inlet over the rim of the tank. For instance, in a 15 inch pipe I preferably use two inch perforations so spaced that the total number of perforations in three lineal feet length of the 15 inch pipe will have a combined area equal to two and one fourth square feet, which is the area of the inlet of the standard mixing head above referred to. Smaller or larger pipes should preferably have correspondingly graduated perforations of size varying directly with the diameter.

This particular ratio of perforation area to inlet area figures to 108 two inch perforations per lineal foot of pipe, and the ratio of perforation area to pipe area is 0.6 to 1.0. This ratio has been demonstrated to give good results in pipes of this size, which are probably as large as would be used in the largest tanks now being built. In pipes of smaller size the ratio of perforation to pipe would have to be greater because of the greater relative resistance of smaller perforations. The object of the perforations is to retain within the down pipe just sufficient head of foam to cause it to emerge mainly through the perforations close to the oil, without jetting through the holes or leaving the outer surface of the pipe other than by flowing down such outer surface. With this object in mind it is easy to determine by simple experiments the correct perforation area (which can be carried over quite a wide range) suitable for any given down pipe size.

While I have shown round perforations, as being the most convenient to form in practice, my invention is by no means limited to such shape, slots or holes of any preferred shape answering the same purpose, which is simply to restrict the outflow area sufficiently to produce a gentle welling out of the foam from the lower perforations. Battery screen

having slot areas suitable to the size pipes to be made may be advantageously rolled up and welded into down pipes of smaller sizes.

While it is not necessary to close or even 5 to substantially close the lower end of pipe 8, it is desirable to do so and I prefer to effect this closure at oil level, by means of a floating piston 11 substantially fitting the inside of pipe 8 but not fitting so closely as to incur 10 any danger of the piston sticking. This piston is closed on the bottom as indicated at 12 and also has a horizontal web indicated at 13, which is preferably placed below the upper end of the piston wall, leaving the 15 open cup indicated at 14. The object of the piston is to prevent foam from escaping from pipe 8 beneath the surface of the oil, and its buoyancy should be such as to cause the upper end of the piston to stand substantially 20 at the level of the oil in the tank, or at a point rather lower than that indicated in the drawing in which the oil level is indicated at 15. For a pipe 15 inches in diameter the buoyancy of the piston should be such that a 25 weight of 100 pounds is required to force it down to the preferred level above described. Pistons of different diameters would obviously require different degrees of buoyancy.

30 The open cup 14 is not an essential part of my invention, though its use is highly desirable. It has been found that where the upper end of the piston is convex or even flat, there is a decided tendency for foam to leak 35 past the piston and make its way out of the perforations below the piston, or even from the bottom of the pipe. This tendency is offset, for reasons which are not fully understood, by providing a substantially concave 40 upper end such as the cup described.

The operation of my invention will already 45 have been made evident by the above description. Foam pumped into the upper end of the perforated pipe 8 flows down inside the pipe and emerges above the piston 14 through the holes 10. Where these holes have such an area that three lineal feet of the pipe provides openings equivalent to the area of the foam inlet, the foam will actually emerge 50 from the pipe for a distance ranging from four to five feet above the top of the piston. The foam thus gently emitted from the relatively small holes is observed to flow down the outside of the pipe in a semi-fluid mass, 55 usually of considerable thickness as measured from the outer surface of the pipe. This mass flows down onto the oil surface 15 with the least possible disturbance of that surface, and spreads out rapidly and evenly into 60 a smooth and unbroken layer. Such small quantities of foam as may emerge from perforations above the level stated will not leave 65 the outer surface of the pipe, but will flow down gently to join the mass of foam flowing out of the lower perforations.

My invention thus provides for the floating on the surface of a layer of burning oil of a consistent layer of fire foam without any danger whatever of the breaking down of the foam or of the projection of masses of foam beneath the surface of the burning oil. 70

I claim as my invention:

1. In a device for placing fire foam on a surface of a layer of oil confined in a tank, an unobstructed pipe extending from the upper portion of the tank to substantially its bottom, said pipe being perforated substantially throughout its entire length with holes having a sufficient combined area to permit the outflow of foam discharged into the upper end of said pipe, each of said holes being of materially less area than the pipe and being unobstructed both within and without said pipe, a piston floating within said pipe, said piston being so constructed as to float substantially at the level of the oil contained in said tank. 75 80 85

2. A device substantially as and for the purpose set forth in claim 1, wherein said piston has its upper end formed into a cup opening upwardly. 90

In witness that I claim the foregoing I have hereunto subscribed my name this 21st day of October, 1927.
